UNITED STATES PATENT OFFICE.

CHARLES E. BLAIR, OF DORCHESTER, MASSACHUSETTS, ASSIGNOR TO AMERICAN
WARP-DRAWING MACHINE COMPANY, A CORPORATION OF MAINE.

DETACHED HEDDLE OR THE LIKE.

1,153,857.

Specification of Letters Patent. Patented Sept. 14, 1915.

Original application filed December 23, 1903, Serial No. 186,301. Divided and this application filed March 12, 1914. Serial No. 824,249.

To all whom it may concern:

Be it known that I, CHARLES E. BLAIR, a citizen of the United States, and a resident of Dorchester, county of Suffolk, State of Massachusetts, (whose post-office address is 195 Freeport street, Dorchester, Massachusetts,) have invented an Improvement in Detached Heddles or the like, of which the following description, in connection with the accompanying drawings, is a specification, like characters on the drawings representing like parts.

This invention relates to detached loom elements such as independent heddles, drop wires, or the like, and more particularly to the construction or arrangement of such heddles so that when assembled in an organized series they may be readily separated one from another.

20 This application is a division of my prior copending application Serial No. 186,301, filed December 23, 1903.

The invention will be best understood by reference to the following description when taken in connection with the accompanying illustration of one specific embodiment thereof, while its scope will be more particularly pointed out in the appended claims.

In the drawings: Figure 1 shows an assemblage of detached heddles embodying one form of my invention, there being also shown in operative relation thereto releasing or separating devices for releasing heddles one by one from the series. Fig. 2 is a perspective view showing the action of the releasing devices on the heddles. Fig. 2^a shows the cap plate for the heddle guide rods; Fig. 3 is a front elevation of a pair of heddles having a special holding formation. Fig. 4 is a front elevation of the heddles of Fig. 3 assembled to present the holding portions in regular, alternate variation; Fig. 5 shows the heddles of Fig. 3 in perspective with the threads drawn through the same; Fig. 6 is a perspective view showing the heddles of Fig. 3 with their holding portions engaged by holding rods; Fig. 7 is a plan view of the heddles shown in Fig. 6; Fig. 8 shows the heddles of Fig. 6 swung into an angular relation with each other; and Fig. 9 is a front elevation of an assemblage of heddles having a modified form.

Referring to the drawings, and first to the

embodiment of the invention shown for illustrative purposes, in Figs. 1, 2 and 2^a, I have there disclosed an assemblage of detached heddles 1 held in series arrangement so as to be capable of ready separation or selection one by one from the series. In the drawings these are represented as flat, metallic heddles of the kind usually formed out of thin, resilient sheet metal, being employed in the loom as drop heddles, but the invention contemplates independent, detached heddles of other forms of construction and also similar loom elements, such as drop bars or drop wires, the term "heddle" being used as a generic term to include those devices as well. The heddles shown in Fig. 1 are arranged one on top of another, each successive heddle of the series being inclined obliquely across the underlying one, so that each pair of heddles forms, as it were, a St. Andrew's cross. This permits the opposite ends of the heddles to be availed of as holding portions by arranging under them suitable detents on which they rest. By withdrawing the detents of the lowermost heddle that heddle may be released and separated from the series while the remaining heddles are held back and preserved in series arrangement by the detents engaging the next adjacent one of the series.

Referring more specifically to the parts shown in Figs. 1 and 2^a, the heddles 1 are secured at opposite ends between pairs of vertical rods or guides 2, the latter fastened to the plate 3 mounted on the support 4. The upper ends of the guide rods are secured to a cap plate 5 (Fig. 2^a) having a depending guide rod 6 passed through the eyes 7 of the heddles, the arrangement being such that the rod 6 in conjunction with the guide rods 2 hold the heddles in a regular alternately varying position for successive members of the series. The plate 3 is provided with diagonal slots having openings 8 which register with complementary openings in the support 4 so that the heddles may have free passage therethrough when permitted to drop one at a time by the detents below. The detents are arranged in pairs 9 and 10, a pair being normally projected in the path of each obliquely arranged row of heddles. This is indicated by the position of the de-

tents 9—9 of Fig. 2. Each detent lever is pivoted upon a block 11 mounted on the support 4 and is connected to suitable actuating devices such as the actuating rod 12, 5 so that both members of a pair are worked in unison, one pair (like 10—10 in Fig. 2) being momentarily depressed, and then the other. The result is that the support provided by the detents is momentarily withdrawn, 10 first from the lowermost heddle of one set or row and then from the next adjacent heddle which lies in the other set or row, the detents for the first set or row, however, having been previously restored to, 15 their normal position. It will be seen by reference to Figs. 1 and 2 that while the detents 10—10 are acting in unison to release the heddles at the bottom of the pile, the diagonally opposite detents 9—9 act in 20 unison to support all the heddles above the bottom one, and that, at each movement of the detents, their positions are reversed, the detents 10—10 next assuming the supporting position and the detents 9—9 the releasing position. The alternate releasing of the heddles is effected by placing each one at 25 an angle to the one above, so that the bottom one always rests upon one pair of detents and supports the pile above it. Then, as the detents are alternately swung downward, the heddles are released one at a time. 30 Any suitable devices for actuating the detents may be used. Inasmuch as such actuating devices are not essential to the present invention, they are not illustrated, the detents themselves being shown to illustrate the utility of the alternate variation of position in the successive heddles. Each heddle when released may be carried to suitable 35 operating devices such as the drawing-in mechanism of a warp drawing machine, or its separation may be utilized for any other desired purpose.

In Figs. 3 to 8, inclusive, I have shown a 40 form of heddle or drop wire also formed of thin, sheet, resilient material, but provided with a special or characteristic holding formation arranged at one side thereof. Referring to Fig. 3 it will be seen that the heddle or drop wire is substantially the same as the ordinary heddle, but at one side of its longitudinal, central axis, it is provided with the lateral projection 13 so that its exterior, linear contour is different on one side from the other, being non symmetrically formed with reference to its axis of suspension. This permits the heddles to be suspended, for example, on a hanger or suspension rod 14, in serial harness arrangement, but with the holding portions of successive heddles arranged in regular, alternate variation such that they occur first on one side of the axis of suspension and then on the other. This provides that the holding portion of any one heddle is entirely un-

covered by the edge of the preceding heddle. This regular, alternate variation in the formation of successive heddles may be availed of in the hand separation of the heddles or drop wires for any desired purpose while the same are suspended or supported in harness formation, or it may be availed of to separate the heddles one from the other by the employment of suitable separating or releasing devices coöperating with the holding portions. It may also be usefully employed as shown in Figs. 5 to 8, inclusive, to separate the heddles into two rows or groups bearing some such angular relation to each other as is represented in Fig. 1. To this end each heddle is provided with an aperture 15 in the holding portion 13. By placing the heddles in the loom initially with the holding portions 15 projecting alternately forward and rearward, they may be removed therefrom upon a rod 16 passed through the eyes thereof, after which rods 17 and 18 may be passed through the apertures 15 and the heddles moved into angular relation to each other as shown in Fig. 8, by simply separating the rods 17 and 18. It is not essential that the holding members 13 should be of any particular shape, it simply being necessary that each alternating heddle should be distinguishable from the adjacent one. To secure this end the thread eyes 7 may be located a little to one side of the central, longitudinal line thereof, so that in that event, when the rod 16 passes through the eyes, the heddles assume a regular, alternate variation in position and can be easily positioned into the angular relation desired. In such a formation the member on the heddle can consist of the slightly larger portion at one side of the eye. Instead of having the member at the upper end of the heddle, the holding member or portion 13 can be formed on the lower portion thereof as shown in Fig. 9.

I believe it to be novel to form heddles which are alternately distinguishable from those beyond them either by broadening one side of the heddle, or by lengthening alternating heddles and I have contemplated these forms in carrying out my invention.

While for illustrative purposes I have herein shown and described one specific embodiment of the invention it is to be understood that the same is not limited to the details or form or arrangement herein shown, but that extensive deviations may be made therefrom without departing from the spirit thereof.

I claim:

1. As a new article of manufacture, a harness consisting of individual, detached, metallic heddles, each composed of thin, resilient sheet material and each having a holding formation, and means for holding them in the form of an organized harness to 130

present the holding formation in regular alternate variation for successive heddles of the harness.

2. As a new article of manufacture, a harness consisting of individual, detached, metallic heddles, each composed of resilient, thin sheet material, and having each a holding formation, means for holding the heddles in the form of an organized harness, the holding formation being presented in a varying position for successive heddles of the series whereby through the operation of heddle releasing means the heddles may be released singly from the series.

15 3. As a new article of manufacture a harness consisting of individual, detached, metallic heddles composed of thin, resilient sheet material, each heddle having its flat face formed to present at some part thereof a holding part, and means for holding said heddles whereby the holding parts of successive heddles are differently positioned and uncovered by the body of the preceding heddle.

25 4. As a new article of manufacture, an independent detached heddle unsymmetrically formed with reference to a longitudinal central axis whereby a series of said heddles may be held in alternate varying arrangement to present each a holding part uncovered by the preceding heddle, the holding part in successive heddles being positioned on opposite sides of the longitudinal central axis of the heddle.

35 5. As a new article of manufacture, a harness composed of a series of independent, detached heddles each having a supporting portion and a holding portion, and means for supporting the same in the form of an organized harness with the holding portions of successive heddles out of line and uncovered by the preceding heddle.

6. As a new article of manufacture, a harness consisting of a series of metallic heddles or the like each composed of a thin, sheet metallic strip and having each a supporting edge, the outline of each heddle undergoing a regular alternating variation in successive heddles with relation to the supporting edge whereby each heddle presents a holding part uncovered by the body of the preceding heddle.

7. The combination with a series of detached heddle members or the like, of means for holding the same in series, each member having a holding portion, the next adjacent member being formed at its edge to entirely uncover said holding portion.

8. The combination with a series of detached, thread-engaging loom elements of means for holding the same to present each a holding portion arranged to lie adjacent a cutaway portion in the next member of the series.

65 9. A harness comprising a series of de-

tached, independent heddles each composed of flat sheet metal and having each a supporting edge, each heddle also having its exterior, linear contour formed to provide a special holding portion non symmetrically arranged with relation to the axis of suspension when suspended on said supporting edge and means to hold said heddles in series with the successive members of the series in alternating arrangement to present each its holding portion uncovered by the preceding heddle.

10. A harness comprising a series of detached, independent heddles each composed of flat sheet metal and each having its exterior, linear contour formed to present a lateral projection, means to hold said heddles in series with successive members of the series in alternate arrangement thereby to present each its lateral projection uncovered by the preceding heddle.

11. A harness comprising a series of detached, independent heddles each composed of flat sheet metal and each having its exterior, linear contour formed to provide a special holding portion non symmetrically arranged with relation to the axis of suspension, and means to hold said heddles in series in alternating arrangement to present each its holding portion uncovered by the preceding heddle.

12. A harness comprising a series of detached, independent heddles each having its exterior, linear contour formed to provide a special holding portion and means to hold said heddles in series with successive members of the series in alternating arrangement thereby to present each its holding portion uncovered by the preceding heddle.

13. As a new article of manufacture a harness consisting of individual, detached, metallic heddles or the like each composed of flat strips of thin, resilient sheet material presenting flat faces whereby the said heddles may be held with substantially their entire flat faces in working contact and in a closely compacted and unseparated bank, each heddle having a threading perforation in its flat face and having also a holding formation, and means for holding said heddles in the form of an organized harness with the major part of the body portion of successive heddles in substantial registration and alinement and with the holding formations in regular, alternate variation for successive heddles of the harness, each holding formation being uncovered by the body of a preceding heddle.

14. As a new article of manufacture a harness consisting of individual, metallic heddles or the like and means for holding them in the form of an organized harness to present each a holding part, the position of the holding parts of successive heddles of the harness having a regular, alternate

- variation and the holding part of one heddle being uncovered by a preceding heddle, said heddles being held with the major part of their body portions in substantial registration and alinement whereby they may be held in a compact bank.
15. As a new article of manufacture a harness consisting of individual, detached, metallic heddles composed of flat strips of thin, resilient sheet material presenting flat faces free from projections whereby the said heddles may be held with their flat faces in close contact and in a compacted series, each heddle having its flat face formed to 10 present at some part thereof a holding part, and means for holding said heddles whereby said holding parts present a regular, alternate variation of position in successive heddles.
16. As a new article of manufacture a harness consisting of individual, detached, metallic heddles or the like, each composed of flat strips of thin, resilient sheet material presenting flat faces whereby the said 15 heddles may be held with substantially their entire flat faces in working contact and in a closely compacted and unseparated bank, each heddle having a threading perforation in its flat face, each heddle having a holding, 20 portion and means for supporting the heddles in the form of an organized harness with the holding portions of successive heddles uncovered each by the preceding heddle.
17. As a new article of manufacture a harness consisting of individual, detached, metallic heddles or the like, each composed of a flat strip of thin, resilient sheet material presenting flat faces whereby the said 25 heddles may be held with substantially their entire flat faces in working contact and in a closely compacted and unseparated bank, each heddle having a threading perforation in its flat face, said heddles being adapted 30 to be suspended in harness and each heddle being unsymmetrically formed with reference to its axis of suspension whereby they 35 present a regular alternate variation in position.
18. As a new article of manufacture a harness consisting of individual, detached metallic heddles or the like, each heddle having a holding portion at one side thereof, and means for holding said heddles with the holding portions of successive heddles 40 alternately arranged on opposite sides of the series.
19. A series of independent heddles consisting each of a flat strip of resilient material presenting flat faces whereby said heddles when required may be held with substantially the entire extent of their flat faces in close contact and in a closely compacted bank with the major part of the body portions of successive heddles in registration 45 or alinement, each heddle having a thread- 50 ing perforation in its flat face, said series being characterized by a regular, alternate variation of position of the members of the series.
20. A series of independent heddles consisting each of a flat strip of resilient material presenting flat faces whereby said heddles when required may be held with substantially the entire extent of their flat faces in close contact and in a closely compacted bank with the major part of the body portions of successive heddles in registration or alinement, each heddle having a threading perforation in its flat face, said series 55 being characterized by a regular alternate variation of form of the members of the series.
21. A series of independent heddles consisting each of a flat strip of resilient material presenting flat faces whereby said heddles when required may be held with substantially the entire extent of their flat faces in close contact and in a closely compacted bank with the major part of the body portions of successive heddles in registration or alinement, each heddle having a threading perforation in its flat face, said series 60 being characterized by a regular, alternate, exterior, linear variation of the members of the series.
22. As a new article of manufacture a harness consisting of individual, detached, metallic heddles or the like composed of flat strips of thin, resilient sheet material presenting flat faces whereby the said heddles may be held with substantially their entire 65 flat faces in working contact and in a closely compacted and unseparated bank, each heddle having a threading perforation in its flat face, and means for holding the heddles in series, each heddle having a holding portion and the next adjacent heddle being formed at its edge to entirely uncover said holding portion.
23. An assemblage of individual, detached metallic heddles or the like composed of flat strips of thin, resilient sheet material presenting flat faces whereby the said heddles may be held with substantially their entire 70 flat faces in close contact and in a closely compacted and unseparated bank, each heddle having a threading perforation in its flat face and having longitudinal straight edges, one edge being interrupted by a lateral enlargement, and means for holding 75 said heddles in series so that the enlargement of each heddle is uncovered by the body of the preceding heddle.
24. As a new article of manufacture a harness consisting of a plurality of detached metallic heddles or the like each composed of a strip of thin, flat, resilient material and having a threading perforation in the flat face thereof and adapted to lie with the flat face of one in close contact with the face 80

of another, said heddles having an alternately varying outline in successive members of the series.

25. The combination with a series of independent, detached metallic heddles each composed of a thin flat strip of resilient sheet material having flat faces and having each a threading opening in its flat face and also a bar-receiving perforation, the latter having edges substantially parallel with the straight edges of the heddle, the heddles of the series undergoing an alternate variation in form, and means for holding said heddles in series in a closely compacted bank with their major body portions in substantial registration, but presenting each a holding portion uncovered by the body of the preceding heddle.

26. The combination with a series of independent, detached, metallic heddles, each composed of a thin, flat strip of sheet material having flat faces and having at one edge an abrupt, characteristic holding projection of relatively small area as compared with the entire face of the heddle, and means for holding the heddles in series and a closely compacted bank with their major body portions in substantial registration but with the holding projections arranged in alternation whereby the holding projection on each heddle is uncovered by the body of the preceding heddle.

27. An assemblage of individual, detached, metallic heddles or the like composed of flat

strips of thin, resilient, sheet material and means for holding said heddles in an alternately crossed relation and with their flat faces in contact, said means comprising a longitudinal holding member passing through a perforation in each heddle and on which said heddles are pivotally held and additional holding means for holding the heddles in the said alternately crossed relation.

28. In an assemblage of individual, detached, metallic heddles or the like composed of flat strips of thin, resilient sheet material, said heddles being formed each with an abrupt projection at one edge of relatively small area as compared with the entire face of the heddle, and means for holding said heddles in an alternately crossed relation with their flat faces in contact and the said holding projections of successive heddles alternately on opposite sides, said means comprising an elongated holding member passing through perforations in the heddles and on which said heddles are pivotally held, and other holding members engaging said heddles and holding them in the said alternately crossed relation.

In testimony whereof, I have signed my name to this specification, in the presence of two subscribing witnesses.
